UNITED STATES PATENT OFFICE.

FRANK M. OVERHOLT AND ARTHUR G. GRANBOIS, OF MINNEAPOLIS, MINNESOTA,
ASSIGNORS OF ONE-HALF TO AMERICAN LINEN COMPANY, OF MINNEAPOLIS,
MINNESOTA, A CORPORATION.

LAUNDRY-MANGLE FEED-HOPPER.

1,226,246.

Specification of Letters Patent. Patented May 15, 1917.

Application filed June 1, 1915. Serial No. 31,446.

To all whom it may concern:

Be it known that we, FRANK M. OVERHOLT and ARTHUR G. GRANBOIS, citizens of the United States, residents of Minneapolis, 5 county of Hennepin, State of Minnesota, have invented certain new and useful Improvements in Laundry-Mangle Feed-Hoppers, of which the following is a specification.

10 In the operation of a laundry mangle, it is customary to dump the clothes as they come from the extractor into a hopper-like receptacle in front of the mangle, where they are picked out piece by piece and fed 15 into the rolls. The hopper is usually filled to the top, or nearly so, and as the clothes are removed it is evident that the mangle attendants must stoop or reach down a little farther until the bottom of the hopper is 20 reached. This constant stooping has been found to be tiresome and laborious and the object of our invention is to provide means for raising the bottom of the hopper so that, as fast as the clothes are fed into the 25 machine, the pile can be raised to a point within convenient reach of the attendants.

A further object is to provide a simple, inexpensive means for raising the hopper and its contents, which can be applied to 30 any type of mangle.

The invention consists generally in various constructions and combinations, all as hereinafter described and particularly pointed out in the claims.

35 In the accompanying drawings forming part of this specification,

Figure 1 is a side elevation of the forward portion of a laundry mangle with our invention applied thereto.

40 Fig. 2 is a plan view of the same, the middle portion of the mangle and hopper being broken away.

In the drawing, 2 represents the frame 45 of the mangle; 3 and 4 the feed belts to which the pieces of flat work, such as sheets, towels, and the like, are delivered for passage over the steam ironing and drying rolls. 5 represents brackets projecting forwardly from the frame of the machine and 6 is a 50 hopper, supported at 7 on the frame of the machine and attached to a shaft 8 that is journaled in bearings in the outer ends of the brackets 5. This hopper preferably consists of a strip of canvas or other suitable

flexible material, which will assume a sack-like form when unwound to its fullest extent and hold a large quantity of the clothes to be ironed. One member of a ratchet clutch 9 is secured on one end of said shaft 8 and the other member 10 is loosely mounted thereon and normally held out of engagement with the member 9 by a tension coil spring 11. A sheave 12 is mounted on the clutch member 10 and has a belt drive 13 with a pulley 14 on the shaft 15 of one of the feed rollers. Normally this belt and the sheave 12 run idle. A lever 16 is mounted to engage the clutch member 10 and has an end portion 17 projecting outwardly where it can be conveniently engaged by the attendant standing in front of the hopper for forcing the clutch member 10 into engagement with the other clutch member 9 to revolve the shaft 8 and wind up the flexible hopper thereon to raise the clothes therein 75 to a point where they can be conveniently reached by the attendant. Backward movement of the shaft is prevented by a ratchet wheel 18 and a dog 19. When the clothes have all been removed from the hopper, the 80 dog 19 may be disengaged from the teeth of the ratchet wheel and when a fresh supply of clothes is deposited in the hopper, the weight of them will revolve the shaft 8 and unwind the hopper, allowing it to drop 85 down to the position indicated in Fig. 1, the ratchet clutch being, of course, disengaged automatically as soon as the attendant releases the lever 16. A stop guide 20 is provided for the inner end of the lever 16. 90

We do not wish to be confined to the particular construction herein shown and described for operating or supporting the lever in the front of the mangle, as in various ways these features may be modified and 95 still be within the scope of our invention.

We claim as our invention:

1. The combination, with a laundry mangle, of a flexible hopper mounted in front of the same and means for winding up one 100 side of said hopper to raise the lower portion thereof and lift the clothes.

2. The combination, with a laundry mangle, of a hopper mounted to extend transversely thereof and trough-shaped in form 105 and adapted to contain clothing piled loosely therein, and means within control of an attendant for raising said hopper to

elevate the clothes therein within convenient reaching distance as the pile in the hopper diminishes.

3. The combination, with a laundry mangle, of a hopper composed of flexible material supported at one edge over the mangle frame, a shaft whereon the other edge of the hopper is mounted, and means connecting said shaft with a moving portion of the mangle for raising the hopper and the clothes therein to a higher level.

4. The combination, with an ironing machine, of a hopper composed of flexible material supported at one end of the machine frame, a shaft whereon the other edge of the hopper is mounted, a driving connection between said shaft and a moving por-

tion of the machine for raising the hopper and the clothes therein to a higher level, and a clutch mechanism within control of the attendant for rendering said driving connection operative or inoperative.

5. The combination, with a laundry mangle, of a hopper composed of flexible material and extending across the front of the mangle, a shaft mounted to wind up one edge of said flexible hopper thereon to elevate the clothes in the hopper, and mechanism within control of an attendant for revolving said shaft.

In witness whereof, we have hereunto set our hands this 21st day of May, 1915.

FRANK M. OVERHOLT.
ARTHUR G. GRANBOIS.
